UNITED STATES PATENT OFFICE

FERDINAND A. SCHAETZKE, OF MILWAUKEE, WISCONSIN

DESIGN FOR A CIGARETTE EXTINGUISHER

Application filed May 10, 1930. Serial No. 35,583. Term of patent 7 years.

To all whom it may concern:

Be it known that I, FERDINAND A. SCHAETZKE, a citizen of the United States, residing in Milwaukee, in the county of Milwaukee and State of Wisconsin, have invented a new, original, and ornamental Design for Cigarette Extinguishers, of which the following is a specification, reference being had to the accompanying drawing, forming part thereof.

The figure is a perspective view of a cigarette extinguisher, showing my new design.

I claim:

The ornamental design for a cigarette extinguisher, substantially as shown.

FERDINAND A. SCHAETZKE.
